Primary Examiner — Jeffrey D Asch(74) *Attorney, Agent, or Firm* — McAndrews Held & Malloy, Ltd.(57) **CLAIM**

The ornamental design for an electronic device, as shown and described.

DESCRIPTION

FIG. 1 is a top right front perspective view of an electronic device showing our new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof; and,

FIG. 7 is a bottom plan view thereof.

The even length dashed broken lines are for environmental purposes only and form no part of the claimed design.

1 Claim, 5 Drawing Sheets(56)
